UNITED STATES PATENT OFFICE

DAVIS MARINSKY, OF NEW YORK, N. Y., ASSIGNOR TO MOLLIE BECKERMAN, OF NEW YORK, N. Y.

FASTENER AND SUSPENDING DEVICE

Application filed August 11, 1928. Serial No. 298,975.

This invention relates to fastener devices and particularly to devices of this class including supporting or suspending straps for supporting garments of various kinds and classes on the body of the wearer, and the object of the invention is to provide a fastener device comprising two cooperating parts within and between which one or more garments are adapted to be clamped, and strap members secured to said parts in such manner as to support the garment or garments in connection with the body of the wearer; a further object being to provide means for adjustably supporting a strap member in connection with the separate parts of the fastener to adjust the strap member of the device or devices to the desired size, and further to compensate for the thickness or thicknesses of the garment or garments of the class used; a further object being to provide a device of the class specified in the form of shoulder straps involving two strap members, having at each end thereof, fastener devices adapted to engage one, two or more body garments both in the front and back of the body of the wearer for supporting said garments in proper position and to eliminate the use of independent strap members for each garment worn as is the common practice, especially in women's and children's garments; and with these and other objects in view the invention consists in a fastener or article of manufacture of the class and for the purpose specified, which is simple and economical in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a front view illustrating one use of my invention.

Fig. 2 is a perspective view of one end of one of the strap members which I employ with the separate parts of the fastener detached.

Fig. 3 is a sectional detail view of one end

of the strap members shown in Fig. 1, the section being on the line 3—3 of said figure.

Fig. 4 is a view similar to Fig. 2 but showing a modification; and,

Fig. 5 is a view similar to Fig. 3 of the modified structure shown in Fig. 4.

For the purpose of illustrating one method of carrying my invention into effect, I have shown my improved fastener device as applied to what are known as shoulder-straps used in supporting ladies' undergarments of various kinds and classes on the body of the wearer, it being understood that my invention is not necessarily limited to this specific use.

In Figs. 1 to 3 inclusive, I have shown one form of construction, and in said figures I have shown a fastener device consisting of two parts 10 and 11, and at 12 I have shown the shoulder-strap to each end of which one of the parts 10 and 11 are mounted. In Fig. 1 of the drawing, I have shown two of the straps 12 passing over the shoulders in the use illustrated.

The part 10, of the construction shown, consists of a substantially rectangular body divided by two transverse bars 13 and 14 to form three transverse apertures 15, 16 and 17, and one end of the part 10 is provided with a projecting tongue 18 having an outwardly projecting knob or button 19. The part 11 is provided at one end with a transverse aperture 20 and the other end portion is provided with a key-hole aperture 21, having an enlarged opening 21^a and a contracted elongated end 21^b through which the shank 19^a of the button or knob 19 is adapted to pass.

In the use of the device consisting of the parts 10 and 11, each end of the strap member 12 is mounted in connection with said parts as follows. The end of the strap 12 is first passed through the aperture 15, then through the aperture 20 in the part 11, then backwardly through the aperture 15, forwardly through the aperture 16, and then backwardly through the aperture 17, the free end of the strap member projecting to a slight extent as indicated at 12^a.

In merchandising the device as illustrated, a set of four of the pair of fasteners 10—11

100

may be sold and, if desired, two pair of these devices may each be attached or affixed to strap members to constitute an article of merchandise which may be sold in a convenient box, card or package, the strap member being of a character and color suitable for general or conventional use.

When the device is applied and assuming the fastener devices are attached to the strap member, one pair of devices on one end of each strap member is secured to the upper end of one or more garments at the back of the body of the wearer, and the strap members are passed over the shoulders and attached to the garment or garments at the front of the body of the wearer. It is understood that one, two or more undergarments may be supported by the use of a single strap member passing over each shoulder of the body instead of using a strap member on each garment, as is the common practice.

In securing the garments in and between the parts 10 and 11 and of each device, the garments are placed upon the knob 19 of the part 10 and the part 11 is placed upon the part 10, passing the knob and the garments upon the knob through the enlarged opening 21^a of the aperture 21, and then sliding the part 11 longitudinally of the part 10 to clamp in the reduced slotted portion 21^b of the aperture and around the neck 19^a of the knob 19, it being understood that the strap member 12 is adjusted as to size prior to securing the garments in position, or in the operation of accomplishing this result it will be understood that the strap member is locked and secured by the looping of the strap member through the aperture 20 and the passage of the same through the apertures 15, 16 and 17 forming a buckled type lock or securing means.

In Fig. 3 of the drawing, I have shown the parts 10 and 11 in attached position, and in said Figure 22 represents the upper edge of two body garments secured in position. A device of the class described will prove to be comfortable to the user and will eliminate the untidiness and inconvenience of a number of strap members passing over the shoulders of the wearer as is the present custom, and also the several body garments may be more securely and firmly retained in position and adjusted upon the body of the wearer.

In Figs. 4 and 5 of the drawing, I have shown a slight modification wherein I have substituted for the parts 10 and 11, two parts 23 and 24, the part 23 having two elongated apertures 25 and 26, and a projecting tongue 27 having an outwardly directed knob or button 28; whereas the part 24 is provided with an elongated aperture 29 and an inverted key-hole aperture 30, the enlarged opening 30^a of which is arranged at the lower end of the part 24. In this construction, the strap member 12 passes backwardly through the aper-

ture 25, forwardly through the aperture 26 and looped through the aperture 29 of the part 24 and then backwardly through the aperture 26.

In the device shown in Figs. 4 and 5 the upper edges of the garment or garments, as indicated at 22^a in Fig. 5, may be secured in position by simply passing the knob 28 through the aperture 30^a but, if desired, the part 23 may be moved vertically or longitudinally of the part 24 to bring the neck 28^a of the knob 28 within the narrow slot 30^b of the aperture 30, as in the construction shown in Figs. 1 to 3 inclusive.

It will be understood that my invention is not necessarily limited to the specific use thereof herein shown and described, and the same may be employed in suspending devices of any kind or class, and the strap members 12 may be of any desired texture and may, if desired, include elastic qualities to eliminate binding. It will also be understood that the separate parts of the fastener devices may be fashioned in any desired manner and from any suitable material, such for example, as metal, fiber, rubber, bakelite, celluloid and other compositions, and various other changes in and modifications of the construction herein shown and described may be made within the scope of the appended claims, without departing from the spirit of my invention or sacrificing its advantages.

Having fully described my invention, what I claim as new and desire to secure by Letters Patent, is:—

1. A device of the class described comprising an elongated strip of predetermined material, interengaging coupling members fashioned from sheet material, one of said members having a plurality of apertures spaced longitudinally through which one end portion of said strip is threaded, the strip being looped through one of said apertures, the other member having an aperture, the loop portion of said strip extending through the aperture of the second named member in adjustably coupling the same with the first named member, and the free end of said strip being threaded through the remaining apertures of said first named member a number of times and extending below said coupling members.

2. A device of the class described comprising two coupling members each fashioned from sheet material, a strap for coupling said members together, said strap being threaded through one of the members a number of times in such manner as to form an extending loop portion, the loop portion of the strap being threaded through the other member, said loop portion forming flexible means for coupling the second named member with the first named member, and the free end portion of said strap extending through the first

named member adjacent the lower end portion thereof.

3. A device of the class described comprising two flat sheet-like members, one of said members having a projecting headed pin portion and the other an aperture adapted to receive the headed pin portion, the first named member having a plurality of longitudinally spaced apertures and a supporting strap the free end portion of which is first threaded through one of the apertures of the first named member and back through said aperture to form a loop which is passed through the second named member, and said end of the strap being arranged to extend beyond the lower end of said first named member in the adjustment of both of said members longitudinally of the strap.

4. A device of the class described comprising two flat sheet-like members, one of said members having a projecting headed pin portion and the other an aperture adapted to receive the headed pin portion, the first named member having a plurality of longitudinally spaced apertures and a supporting strap the free end portion of which is first threaded through one of the apertures of the first named member and back through said aperture to form a loop which is passed through the second named member, said end of the strap being arranged to extend beyond the lower end of said first named member in the adjustment of both of said members longitudinally of the strap, and the end of said strap being threaded through other apertures in the first named member prior to extending therefrom.

In testimony that I claim the foregoing as my invention I have signed my name this 8th day of August, 1928.

DAVIS MARINSKY.
